UNITED STATES PATENT OFFICE.

LORING Q. WHITE, OF PALM BEACH, FLORIDA, ASSIGNOR TO L. Q. WHITE SHOE COMPANY, OF BRIDGEWATER, MASSACHUSETTS, A CORPORATION OF MASSACHUSETTS.

INSOLE.

Application filed April 12, 1927. Serial No. 183,166.

This invention relates to insoles of that type in which the inseam-receiving rib is formed by a cord which is embodied in the insole. The insole embodying the present invention comprises a base layer of leather and an inseam rib-forming layer preferably of fabric, said latter layer being formed with a groove extending adjacent its marginal portion in which groove a cord is laid.

10 A distinctive feature of the present invention is that the cord is secured in a groove or fold of the fabric layer by stitches which are located entirely in said fabric layer and do not extend through the leather layer and that the leather and fabric layers are united by means other than the stitches so that when the insole is built into the shoe the top face thereof will be free from stitches.

20 In order to give an understanding of the invention I have illustrated in the drawings a selected embodiment thereof which will now be described after which the novel features will be pointed out in the appended claims.

Fig. 1 is a perspective view of an insole embodying my invention;

Figs. 2 and 3 are perspective views of the fabric layer with the cord secured thereto, 30 said views showing opposite sides of the fabric layer;

Fig. 4 is an enlarged sectional view on the line 4—4, Fig. 1.

In the drawings 1 indicates generally the 35 insole which is formed with the inseam-receiving rib or lip 2. The insole is of that known type in which this rib or lip 2 is formed by a cord which is incorporated in the insole.

40 In the construction herein illustrated the complete insole comprises a base layer 3 of leather or the like and a fabric layer 4 which has the cord 5 incorporated therein. This fabric layer may be made of a single ply of 45 fabric or of two or more plies as desired. In the construction shown it is composed of two plies 6 and 7, the ply 6 being of burlap or of similar nature and the ply 7 being of a fabric of a finer weave such as cheesecloth. 50 These two plies are adhesively united to make a unitary layer 4. The layer 4 whether of a single fabric or a compound layer, is formed with a groove 8 in which the cord 5 is received and means are provided for securing the cord in the groove

which means are independent of the means for attaching the two layers 3 and 4 together.

In the illustrated embodiment of my invention the cord is retained in the groove by 60 stitches 10 which overlie the cord and are anchored in the fabric layer 4 at either side of the cord as indicated by the two lines of stitching 11. Therefore, the stitches which unite the cord 5 to the fabric layer are situated entirely in the fabric layer. When the cord is thus anchored in the fabric layer it will be provided with a rib 2 on one face which is formed by the cord 5 occupying the groove 8 and the face 12 of said layer will 70 be relatively flat, the cord coming substantially flush with said face. The cord is firmly anchored in the groove by the stitching 10 so that the cord and layer 4 constitute 75 a unitary structure. After the layer 4 has thus been completed with the cord embodied therein then said layer 4 with the cord is secured to the layer 3 by means which are 80 separate and independent from the stitching 10.

Any suitable way of uniting the two layers 3 and 4 may be employed. I will preferably, however, unite them both by means of adhesive which is applied to the contacting faces of the two layers and further by 85 means of staples 13 or other fastening devices which is entirely independent from the means that unites the cord to the fabric layer 4.

By reason of the construction of the insole, which perhaps is shown best in Fig. 4, the face 14 of the insole, which is the top face thereof when the insole is built into the shoe, is entirely free from stitches inasmuch as the stitches 10 do not pass through the 95 leather layer but are located entirely in the fabric layer.

It is not necessary that the staples 13 should be used for uniting the layers 3 and 4 as they may be satisfactorily united by 100 adhesive. If no staples are used then the upper face 14 of the insole will have no indication thereon of any stitches or other fastening means and the insole will thus have the appearance of a solid leather insole. If staples 13 are used they will be placed at the very edge of the insole and may be so small and so thoroughly embedded in the leather layer as to be hardly visible.

An insole embodying this construction 110

can be inexpensively made and it provides an inseam-receiving rib of great strength for holding the inseam stitches of a welted shoe.

5 I claim:

1. An insole comprising a leather layer, a layer of fabric having a fold formed therein adjacent the marginal edge, a cord in said fold, means securing the cord in the

10 fold, and other means independent of the cord for uniting the fabric layer and the leather layer, said cord and fold forming an inseam-receiving rib, said cord being retained in place only by the fold and said

15 first-named means.

2. An insole comprising a leather layer, a layer of fabric having a fold formed therein adjacent the marginal edge, a cord in said fold, stitches located entirely in the

20 fabric layer for securing the cord in the fold, and means other than said stitches for uniting the fabric layer to the leather layer, said cord and fold forming an inseam-receiving rib, said cord being retained in place only

25 by the fold and said stitches.

3. An insole comprising a leather layer, a layer of fabric having a fold formed therein adjacent the marginal edge, a cord in said fold, stitches connecting the sides of the fold and lying across the exposed face 30 of the cord for retaining the cord in the fold, said stitches constituting part of the insole before it is incorporated in a shoe, and means other than the stitches for securing the fabric layer to the leather layer, said 35 cord and fold forming an inseam-receiving rib.

4. An insole comprising a leather layer, a layer of fabric having a fold formed therein adjacent the marginal edge, a cord in said 40 fold, stitches located entirely in the fabric layer for securing the cord in the fold, said stitches constituting part of the insole before it is incorporated in a shoe, said fabric layer being adhesively united to the leather 45 layer, and staples for securing the two layers together at points exterior to the fold.

In testimony whereof, I have signed my name to this specification.

LORING Q. WHITE.
